US0D1053986S

(12) **United States Design Patent** (10) **Patent No.:** **US D1,053,986 S**
(45) **Date of Patent:** **** Dec. 10, 2024**

(54) **AERATOR FOR TAP**

(71) Applicant: **Xiamen Water Nymph Sanitary Technology Co., Ltd., Xiamen (CN)**

(72) Inventor: **Fang Zheng, Fujian (CN)**

(**) Term: **15 Years**

(21) Appl. No.: **35/519,062**

(22) Filed: **Jul. 19, 2023**

(80) **Hague Agreement Data**

Int. Filing Date: **Jul. 19, 2023**

Int. Reg. No.: **DM/233052**

Int. Reg. Date: **Jul. 19, 2023**

Int. Reg. Pub. Date: **Nov. 17, 2023**

(30) **Foreign Application Priority Data**

Jan. 19, 2023 (CN) 202330029191.4

Primary Examiner — Keith J Wilson

(57) **CLAIM**

The ornamental design for an aerator for tap as shown and described.

DESCRIPTION

1.1: Front

1.2: Back

1.3: Left

1.4: Right

1.5: Top

1.6: Bottom

1.7: Perspective

1.8: Perspective

1.9: Perspective view where a filter is attached.

The broken lines shown in the figures depict environment and form no part of the claimed design.

1 Claim, 9 Drawing Sheets
